UNITED STATES PATENT OFFICE.

RICHARD A. ENGLER, OF DUBUQUE, IOWA.

MEGAPLEX RELAY.

SPECIFICATION forming part of Letters Patent No. 757,184, dated April 12, 1904.
Application filed July 13, 1903. Serial No. 165,248. (No model.)

To all whom it may concern:

Be it known that I, RICHARD A. ENGLER, a citizen of the United States, and a resident of Dubuque, in the county of Dubuque and State of Iowa, have invented a new and Improved 5 Megaplex Relay, of which the following is a full, clear, and exact description.

My invention relates to relays, and more particularly to a type of relay for increasing 10 the effect of feeble currents—such, for instance, as are employed in telephony.

Reference is to be had to the accompanying drawings, forming a part of this specification, in which similar characters of reference indicate corresponding parts in all the figures.

Figure 1 is a cross-section through the relay-board, showing one of the individual relay mechanisms. Fig. 2 is a plan view of the same, and Fig. 3 is a diagrammatic view showing one method of connecting up the several individual relay mechanisms of my megaplex relay.

Mounted upon a board 1 is a brass plate 2, provided with extensions 2^a 2^b, as shown best 25 in Fig. 2. Upon the extension 2^a is a post 3, provided with a boss 4, of insulating material, which supports a bell-shaped casing 5. Mounted upon the boss 4 and within the casing 5 is a metallic disk 6, immediately adjacent to 30 which hangs a spring-wire 7, provided at its lower end with a carbon button 8. The diaphragm is shown at 9 and is mounted in the usual manner. The diaphragm 9, carbon button 8, spring-wire 7, and metallic disk 6, with 35 their electrical connections, constitute a microphone substantially of the kind ordinarily employed.

Mounted rigidly upon the diaphragm 9 is an iron lever 10, provided with a sloping portion 40 11 and with a pedestal 12, which is secured to the diaphragm 9 by means of a screw 13. This iron lever 10 projects a little distance 45 out from the diaphragm, so that any slight movement of the outer or free end 11 of the lever 10 causes the diaphragm 9 to press with considerable force upon the carbon button 8.

A permanent magnet 14 is provided with a slot 14^a in one of its poles, and the iron lever 50 10 is disposed within this slot 14^a, but out of

contact with the magnet 14. By this arrangement the iron lever 10 is polarized—that is to say, a portion of the iron lever being in close proximity to the magnet 14 causes the lever to acquire polarity. The lever is thus polarized, 55 so that the portion 11 is a magnet-pole, preferably of considerable power.

A plate 15, of steel, rests loosely upon the plate 2 and is provided with slots 16 17 of the shape indicated in Fig. 2, said plate constituting one of the poles of the magnet 14. A screw 18 passes through the slot 16 into the plate 2 and normally binds generally upon the upper portion of the plate 15, so as to steady said plate, but not to render it immovable. A post 19 is mounted upon the plate 15 and is engaged by a leaf-spring 20, which normally presses the post to the right, as indicated in Fig. 1. This leaf-spring 20 is mounted upon a post 21, provided with an aperture 70 21^a, through which loosely passes a screw 22, mounted rigidly upon the post 19. A milled head 23 is revolubly mounted upon the screw 22 and may be rotated by the fingers, so as to draw the post 19 and plate 15 to the left or to 75 allow them to recede to the right, as desired.

The plate 2 is secured rigidly in position by means of screws 24. A vertical screw-stem 25 is provided with a milled head 26 and passes through the slot 17 in the plate 2. By adjusting the screw 18 and the milled head 26 any desired degree of pressure may be exerted upon the plate 15. The plate 15 is normally clamped firmly upon the plate 2, but may be loosened by relaxing the pressure of 85 the milled head 26.

An induction-coil 27 is provided with primary terminals 28 29, which are connected by the wires 28 29^a with the respective binding-screws 30 31. This induction-coil is also 90 provided with secondary terminals 32 33, which are respectively connected by wires 32^a 33^a with binding-posts 34 35.

A number of the separate relay mechanisms such as have been described are mounted side by side upon a single board. This board forms the unit of the system, and, of course, may be multiplied indefinitely. In Fig. 3 is shown a diagrammatic representation of several of the relay mechanisms. In this in- 100

stance the connections are for the most part in series; but I do not limit myself to the arrangement shown, for obviously the several relay mechanisms may be connected up in any desired manner, including several different methods of connecting up the batteries with the several primary windings.

By means of binding-posts 36 37 wires 38 39 are connected respectively with the spring-wire 7 and the metallic disk 6, so that the wires 38 39 constitute the terminals of the microphone above described. The induction-coil 27 is provided with a core 40, the upper end 41 of which is beveled into conformity with the shape of the portion 11 of the iron lever or armature 10. The core 40 is permanently magnetized by induction from the steel plate 15, constituting one of the poles of the magnet 14, and the lever 10 is always under more or less tension.

Connected with the first of the system of relay mechanisms is a microphone 42, as indicated in Fig. 3. From this microphone a wire 43 leads to a battery 44, whence a wire 45 leads to the primary terminal 29^a of the first induction-coil 27. From the other primary terminal 28^a of the first coil a wire 46 leads back to the microphone 42, thus completing the circuit through the primary terminal. From the secondary terminal 32^a of the first induction-coil 27 a wire 47 leads away from the instrument and forms one of the leads to be energized by the relay as a whole. For convenience the several individual groups of relay mechanisms are designated in Fig. 3 by the letters A B C D. From the secondary terminal 33^a of the coil 27 at A a wire 48 is connected serially with the secondary terminal 32^a of the next coil 27 at B. From the secondary terminal 33^a of this coil a wire 49 is connected serially with the secondary terminal 32^a of the next coil 27 at C. From the secondary terminal 33^a of this coil a wire 50 leads to the secondary terminal 51^a of the induction-coil 51. This coil is of a little different pattern from those already described and is not supplied with the armature 10, as are the other coils. From the secondary terminal 51^b of the coil 51 a wire 52 leads out from the system, this wire and the wire 47 constituting the main terminals of the entire system. It is these wires which are connected directly with the line-wire to be energized or which are themselves the line-wires, if so desired.

A number of separate batteries 53 are connected with the system, as shown in Fig. 3. From the first microphone of the series, located at A, a wire 54 leads to one of the batteries 53. From this battery a wire 55 leads downward and is connected with the primary terminal 28^a of the coil 27 at B. The relay mechanisms disposed at B and C are similarly connected. From each microphone disposed at A B C a wire 56 leads to the primary ter-

minal 29^a of the next succeeding coil 27, as indicated in Fig. 3.

My invention is used as follows: The several parts being connected in the manner described, we will suppose that a person talks into the microphone 42. (Shown at the left in Fig. 3.) The battery 44 energizes the core 40 of the induction-coil at A, and the core 40 is energized by means of a variable current, as is well understood in the art. This causes the core 40 at A to attract the portion 11 of the armature 10 and to release the same in rapid succession, owing to the variations produced by the microphone 42 in the current from the battery 44. The variable magnetic impulses thus given by the core 40 to the armature 10 causes the diaphragm 9 to bear with greater or less pressure against the carbon button 8, thereby operating the microphone at A. When this microphone is thus actuated, the current from the battery 53 passing through the wires 54 56 energizes the core 40 of the induction-coil 27 located at B. The action of the core 40 at B upon the armature 10 at B likewise causes the microphone at B to energize the core 40 at C, and the action of this core in turn similarly energizes the core of the coil 51 at D. Each time the core 40 is subjected to a variation in the strength of the current exciting it the field of force surrounding the core of course acts inductively upon the secondary winding of the coil. The result is that the variation in the several primary circuits generate momentary currents in the several secondary windings, the intensity in each secondary winding being equal to that of the secondary winding of the coil usually employed in telephony. When these windings are connected serially, as indicated in Fig. 3, it is obvious that all of the secondary currents have at any particular moment the same direction, so that their intensity is cumulative. By this means the delicate movements in the microphone 42 cause great variations in the strength of the current flowing through the wires 47 and 52. These currents are also due in a great measure to the addition of many secondary currents.

I am aware that in the systems ordinarily employed the use of an induction-coil or transformer is very common. That a primary winding may excite a core and a core in turn may produce a current of great intensity in a secondary winding is a foregone conclusion. I am not aware, however, that the field of force used in energizing and deenergizing the core of an induction-coil has been made to operate an armature, which in turn automatically actuates a microphone, the microphone actuated by one armature being used to actuate the next induction-coil.

By the arrangement above described a much greater value is given to the sound-waves in the starting-microphone 42 than can be secured by the ordinary arrangement, for the

reason that each successive diaphragm vibrates with the same energy as that of the microphone 42. The magnetism that induces the current in each secondary winding is in turn employed to operate another microphone. The field of force upon each core is continually appearing and disappearing, or rather is continually varying, and I see nothing to prevent the energy otherwise thus wasted from actuating the lever which controls the diaphragm of another microphone. The logic of this statement is found in the fact that only a comparatively small proportion of the energy of the field is utilized in the ordinary system, most of the energy going to waste.

The word "megaplex" as herein used is intended to convey the idea of an amplifying device used for strengthening electric pulsations and undulations, its structure being such as to increase the effect in various ways, and especially to permit several distinct devices to act cumulatively.

Having thus described my invention, I claim as new and desire to secure by Letters Patent—

25 1. In a megaplex relay, the combination of a microphone, an induction-coil having primary terminals connected therewith and also having secondary terminals, a battery connected with said microphone and with said primary terminals, another microphone connected with said induction-coil and actuated thereby for controlling an independent circuit, and electrical connections for said secondary terminals of said induction-coil and for said independent circuit.

2. In a megaplex relay, the combination of a plurality of microphones and a plurality of induction-coils, each of said induction-coils being provided with primary and secondary terminals and each of said microphones being connected in series with the primary terminals of another induction-coil, the secondaries of said induction-coils being connected in series with the line.

3. In a megaplex relay, the combination of a plurality of microphones, and a plurality of induction-coils, each induction-coil being provided with primary and secondary terminals, and each of said microphones being connected in series with the terminals of an induction-coil, the secondaries of said induction-coils being connected in series with each other and with the line.

4. In a megaplex relay, the combination of a number of induction-coils each having a core together with primary and secondary terminals, microphones having an armature controllable by the magnetic field of said cores, electrical connections for said microphones, and wiring connecting said secondary terminals in series with each other.

5. In a megaplex relay, the combination of a plurality of induction-coils, each provided with a core together with primary and secondary terminals, a plurality of microphones con-

nected with said primary terminals and also connected with a source of electricity for the purpose of energizing said cores, and electrical connections for binding said secondary terminals in series with each other.

6. In a megaplex relay, the combination of a plurality of induction-coils, each provided with a core together with primary and secondary terminals, and a plurality of microphones connected with said primary terminals and also connected with a source of electricity for the purpose of energizing said cores, said secondary terminals of the several induction-coils being connected in series with each other and with the line.

7. In a megaplex relay, the combination of a stationary member, a movable member mounted thereupon, an induction-coil mounted upon said movable member and provided with a core, a stationary microphone provided with an armature disposed adjacent to said core, and means for adjusting the distance between said core and said armature.

8. In a megaplex relay, the combination of an induction-coil provided with primary and secondary windings and a microphone and a source of electricity connected with said primary winding, a microphone disposed adjacent to said induction-coil and provided with a movable armature actuated directly by the magnetic influence thereof, a source of electricity connected with said last-mentioned microphone, and another induction-coil having a primary and a secondary winding, said primary winding being connected with said last-mentioned microphone and said secondary winding being connected with said secondary winding of said first-mentioned induction-coil.

9. In a megaplex relay, the combination of an induction-coil provided with a primary and a secondary winding, a microphone connected with said induction-coil and actuated by the magnetic attraction thereof, a source of electricity connected with said microphone, another induction-coil provided with a primary and a secondary winding, wiring connecting the primary winding of said last-mentioned coil with said microphone, and means for connecting the secondary windings together in series with each other and with the line.

10. In a megaplex relay, the combination of a plurality of induction-coils each provided with a primary and a secondary winding, means for connecting the several secondary windings in series with each other and with the line, a microphone disposed adjacent to each of said induction-coils and provided with a vibratory armature actuated by the magnetic attraction thereof, and electric connections between said microphone and the primary winding of one of said induction-coils.

11. In a megaplex relay, the combination of an induction-coil provided with primary and secondary windings, a microphone having a vibratory magnetic member disposed adjacent

to said induction-coil and actuated by the magnetic attraction therefrom, the arrangement being such that the space between said vibratory armature and said induction-coil is greater at one moment than at another for the purpose of controlling the magnetic influence of said induction-coil upon said vibratory armature, the currents generated in said secondary winding being varied thereby, and means for rendering cumulative the effects of

said currents generated by said secondary winding and said microphonic currents.

In testimony whereof I have signed my name to this specification in the presence of two subscribing witnesses.

RICHARD A. ENGLER.
